UNITED STATES PATENT OFFICE.

JACOB MERZON, OF NEW YORK, N. Y.

TALKING-MOTION-PICTURE APPARATUS.

Application filed January 8, 1927. Serial No. 159,757.

This invention relates to motion picture machines and more particularly to types conjunctively operated with talking machines.

One of the objects of this invention is to provide means for recording or reproducing sound simultaneously with projecting motion pictures.

Another object is in the provision of means whereby the sound producing machine may be stopped at predetermined intervals while the motion pictures continue to operate, so that when a character has ceased to emit voice its actions are still recorded on the picture reel.

15 A still further aim is in the provision of apparatus whereby the necessity of flashing words on a screen is avoided, the device instead actually sounding the words as they are spoken by the characters on the screen.

20 These and other important objects which will become apparent as the description progresses, are accomplished by the novel construction, combination and arrangement of parts, hereinafter described and illustrated 25 in the accompanying drawing, forming a material part of this disclosure, and in which:—

Figure 1 is a front elevational view of a talking motion picture apparatus, made in accordance with the invention, and showing the manner of electrically connecting the same, part of the picture machine casing being broken away to illustrate the inner construction.

25 Figure 2 is a fragmentary partial side elevational, partial longitudinal sectional view of a tape actuated switch drawn to an enlarged scale.

Figure 3 is a transverse sectional view of the same.

Figure 4 is a perspective view of the stationary element of the switch.

The numeral 10 designates a table provided with wheels 11 and a cross-support 12 intermediate the legs.

Fixed on the table is a U-shaped bracket 13 in which are formed pairs of bearings 14 and 15, one of the bearings 14 being split and hinged, to be held in operative positions 0 by a wing nut 16 engaging a bolt 17 passing through flanges 18 formed on the sections of the bearing.

The bearings 15 are connected by a guide rod 19 on which is movable a slide 20 having 5 a conventional reproducing instrument 21 at right angles thereto, provided with a needle

22 to transmit vibrations to the diaphragm of the reproducer, the same being connected by a flexible tube 23 to a horn or sound box 24.

60 The needle 22 engages a large cylindrical record 25 removably engageable on a roller 26 similarly journaled in the bearings 14.

Fixed on one extending end of the roller 26 is a crank handle 27 and a pulley 28 so 65 that the record 25 may be rotated either by hand or in a manner to be later described.

Trained over the pulley 28 is an endless belt 29 also trained over a pulley 30 fixed on the shaft 31 of an electric motor 32 secured on the support 12, one terminal of the motor being connected by a lead 33 to a source of electrical energy 34.

70 The other terminal of the motor is connected by a wire 35 to a post 36 engaging a 75 spring contact 37 fixed on a flange 38 of an insulating sleeve 39 having a square opening 40 by which the sleeve is secured on a bolt 41 engaged by a nut 42, the bolt extending outwardly from one of the side walls 43 of 80 a motion picture machine 44 on a support 44'.

A similar post and spring contact is oppositely disposed on the flange 38 and is connected by a wire 45 to the free terminal of 85 the source of electrical energy 34.

Rotatable on the sleeve 39 intermediate the flange 38 and wall 43, is a collar 46 of similar material to the sleeve, provided with a plurality of paired lugs 47 carrying therebetween rollers 48 and pinned at 49 to the collar is a metal disc 50 having oppositely disposed projecting conductors 51 engageable with the contacts 37.

90 The motion picture machine 44 includes 95 the usual supply and take-up reels 52 and 53 respectively and a film 54 movable from the reel 52 to the reel 53 between a pair of similar rectangular frames 55 hinged at 56 to the wall 43.

100 The shafts supporting the reels 52 and 53 extend beyond the wall 43 and carry supply and take-up reels 57 and 58 respectively, provided with a tape 59 passing over the collar 46, the tape being provided with predetermined openings 60 reenforced by grommets 61.

105 The reel 58 may be rotated by a handle 62 or the tape 59 may be operated from a motor (not shown) connected by a belt 63 to a pulley 64 fixed on the shaft carrying the reel 57.

110 Thus, in operation, the voice of the actors

and their movements may or may not be recorded simultaneously, as desired.

In either case, the tape 59, which is intact at the start, is operated simultaneously with 5 the rotation of the record 25.

The voice is recorded in the usual manner, the sound entering the horn 24, passing through the reproducer 21 and being impressed upon the record 25 by the vibration 10 of the needle 22.

During the enactment, whenever there is a stop in the voice, the operator makes a mark on the tape 59 and the play goes on until it is again desired to record sound, at 15 which time the operator again marks the tape.

When the play is completed, each mark, corresponding to a stop or start of sound is 20 perforated and reenforced by a grommet 61.

Thus, that particular tape is inseparable from that record, since it is predeterminedly 25 perforated to conform with the silent periods during the play.

The next step is to "take" the motion pictures.

During this process, the actors emit no sound, but instead merely go through the motions in accordance and time with the impressions on the record 25.

When the film is projected, it is operated simultaneously with the tape 59 and the talking machine is placed out of sight behind the screen.

Thus, when the character on the screen is 30 about to talk, one of the predetermined openings 60 in the tape 59 engages one of the rollers 48, revolving the collar 46 so that the conductors 51 engage the contacts 37 completing the circuit to operate the motor 32, 35 hence to rotate the record 25 and reproduce the voice corresponding to the characters shown on the screen.

When that character finishes talking, another predetermined opening in the tape, 40 operates the collar to break the motor circuit and so stop the talking machine.

From the foregoing, the construction and operation of a simple means for combining motion pictures and a talking machine, has 45 been disclosed, and although the apparatus has been depicted and delineated in its preferred form, it is to be understood that the same is merely descriptive and it is not to be interpreted in a limiting sense, since changes 50 in construction and details thereof may be made without departing from the spirit or scope of the appended claims.

Having thus described my invention, what I claim as new and desire to secure by Letters 55 Patent, is:—

1. A talking motion picture apparatus comprising in combination with a reproducing instrument of the cylindrical record type and a motion picture exhibiting ma-

chine, of means intermediate said instrument 65 and machine for causing said instrument to operate in accordance with the showings on the screen of said machine, said means including a non-metallic tape having reinforced openings at predetermined points, 70 an electric motor to drive said instrument, means for driving said machine and tape synchronously, a rotatable switch in the electric circuit to the motor, and projections on said switch engageable in the openings of 75 said strip to alternately open and close the switch thereby synchronizing said instrument with said machine.

2. A talking motion picture apparatus comprising in combination with a reproducing instrument of the cylindrical record type and a motion picture exhibiting machine, said instrument having an electric motor, of a switch in the circuit to said motor, said switch including a collar rotatable on said machine, rollers projecting from said collar, and means including a perforate tape operated by said machine engageable with said rollers to open and close 80 said switch, thereby to control said motor in synchronism with the projections of said machine.

3. A talking motion picture apparatus comprising in combination with a reproducing instrument of the cylindrical record type and a motion picture exhibiting machine driven in synchronism with said instrument, of an electrical driving means for said instrument including a switch having a collar rotatable on said machine, rollers projecting from said collar, a pair of reels on said machine, a predeterminedly perforated tape intermediate said reels independent of the picture film, said film and tape being driven in synchronism, said rollers being engageable in the perforations of said tape and means on said collar to complete an electrical circuit for actuating said instrument.

4. A talking motion picture apparatus comprising in combination with a reproducing instrument of the cylindrical record type and a motion picture exhibiting machine, said instrument being electrically driven, of a switch in the circuit of the driving means intermediate said instrument and machine including a sleeve fixed on said machine, spring contacts on said sleeve, a collar rotatable on said sleeve, lugs formed on said collar and rollers intermediate said lugs, and a tape driven by said machine and perforated in a predetermined manner to actuate said switch by engagement with said rollers so that successive perforations alternately open and close the circuit.

Signed at New York, in the county of 125 New York and State of New York, this 14th day of December, A. D. 1926.

JACOB MERZON.
